UNITED STATES PATENT OFFICE.

ADDISON J. CLEVENGER, OF ONTARIO, AND CHARLES C. FIELD, OF SODUS, NEW YORK.

TUNING-PIN.

SPECIFICATION forming part of Letters Patent No. 727,589, dated May 12, 1903.

Application filed April 16, 1902. Serial No. 103,195. (No model.)

To all whom it may concern:

Be it known that we, ADDISON J. CLEVENGER, residing at Ontario, and CHARLES C. FIELD, residing at Sodus, in the county of Wayne and State of New York, citizens of the United States, have invented a new and useful Tuning-Pin, of which the following is a specification.

The object of the present invention is to provide an improved form of tuning-pin for use in pianofortes and musical instruments of similar character where strings are employed with a view of obtaining a greater delicacy of adjustment of the pitch of the strings and to retain the instrument in tune for a much longer period of time than is possible with the tuning-pins and methods of tuning in ordinary use.

With these and other objects in view the invention consists in the novel construction and arrangement of parts hereinafter described, illustrated in the accompanying drawings, and particularly pointed out in the appended claims.

In the drawings, Figure 1 is a perspective view of a tuning-pin constructed in accordance with our invention, the pin being shown on an exaggerated scale in order to more clearly illustrate the construction. Fig. 2 is a longitudinal sectional elevation of the pin. Fig. 3 is a sectional plan view of the same on the line 3 3 of Fig. 2.

Similar numerals of reference are employed to indicate corresponding parts throughout the several figures of the drawings.

5 designates a pin proper having a slightly pointed lower end 6 and provided with the usual slightly-indented helical groove 7, the extreme upper end of the pin having a rectangular and tapered portion for the reception of the ordinary tuning-wrench, which is applied in the usual manner to turn the pin. At a suitable point in the pin, as at the point where the usual string-receiving opening is made, is a diametral perforation 9 for the reception of a pin 10, the opposite ends of which project slightly beyond the periphery of the pin, and above the pin 10 the periphery of the tuning-pin is provided with a threaded 50 portion 11 for the reception of a nut 12, which may have a polygonal outer surface

for the application of a suitable wrench, but is preferably formed as illustrated in the drawings, the upper edge of the nut being provided with recesses 13, adapted to receive 55 depending lugs 14, forming part of a cylindrical wrench 15, which may be fitted over the upper end of the key.

16 designates the sleeve or collar, in which are formed two helically-disposed slots 17, 60 adapted to receive the opposite ends of the pin 10, said slots extending in an inclined or curved line around the sleeve or collar for an angular distance about ninety degrees. On the periphery of the sleeve is a laterally-projecting pin 19, to which the end of the string may be secured.

In using the device the slightly-pointed end of the tuning-pin is inserted in the opening in the wrest-plank or other support and by 70 the application of a suitable tuning-wrench the pin is turned, the string of course having been previously secured to the pin or lug 19. Owing to the resistance offered by the string, the pin 10 will be forced against the inner 75 and lowermost ends of the groove 17 on each side of the sleeve and will remain in such position until the string has been properly stretched and is approximately in tune. The pin is then driven home in the usual manner. 80 To then obtain the more delicate adjustment of the string without disturbing the tuning-pin, the nut 12 is placed on the threaded portion of the tuning-pin and is turned by the application of the wrench 15. As the nut is forced 85 down it comes into contact with the upper ends of the collar 16 and forces the latter downwardly, resulting in a slight turning movement of said collar as the inclined walls of slots 17 are pressed against the projecting 90 ends of the cross-pin 10. The slots are of sufficient length to permit a movement of the collar through an angle of about ninety degrees, so that it is possible to accurately adjust the pitch of a string without loosening or turning 95 the tuning-pin after the latter has once been secured in place. The screw-threads 11 are preferably of comparatively fine pitch and inclined to such a small extent that the wrench is able to exert powerful leverage on the collar, and after the latter has been moved and the desired pitch obtained the nut is allowed 100

to remain in position to firmly lock said collar in place.

The construction of the device is such that it may be applied to pianofortes and other instruments now in use without any change in construction and at very little expense.

While the construction herein described, and illustrated in the accompanying drawings, is the preferred form of the device, it is obvious that various changes in the form, proportions, size, and minor details of the structure may be made without departing from the spirit or sacrificing any of the advantages of our invention.

Having thus described our invention, what we claim is—

1. In a device of the class specified a pin member, a helically-grooved string-attaching collar carried thereby, a pin carried by the pin member and projecting into said grooves, and means for forcing the collar longitudinally of the said pin member.

2. In a device of the class specified, a pin member having a projecting pin and provided with an upper threaded portion, an adjustable nut adapted to said threaded portion, and a helically-grooved string-attaching sleeve mounted on the pin member and adapted to receive the ends of said pin.

3. In a device of the class specified, a pin member having a projecting pin or lug, a string-attaching collar mounted on the pin

member and having a helical groove for the reception of said pin or lug, a nut 12 adapted to an upper threaded portion of the pin member and engaging the upper surface of the collar, said nut having a notched upper end, and a wrench having lugs adapted to engage said notches, substantially as specified.

4. In a device of the class specified, a pin member having an upper tapered and angular end portion for engagement by a tuning-wrench, said pin being provided with a diametral opening 9, a pin 10 extending through said opening and having its opposite ends 45 projecting beyond the periphery of the pin member, the upper portion of the pin being provided with screw-threads 11, a ring-nut 12 mounted on said screw-threads and having slots or recesses 13 in its upper edge, a cylindrical wrench 15 having depending lugs 14 adapted to engage said slots or recesses, and a string-attaching sleeve adapted to be engaged by the nut, said sleeve having helical grooves 17 for the reception of the said ends 55 of the pin 10, substantially as specified.

In testimony that we claim the foregoing as our own we have hereto affixed our signatures in the presence of two witnesses.

ADDISON J. CLEVENGER.
CHARLES C. FIELD.
